UNITED STATES PATENT OFFICE

154,843

DESIGN FOR A PHONOGRAPH PICKUP

Joseph J. Esse, Lakewood, Ohio, assignor to The
Brush Development Company, Cleveland, Ohio,
a corporation of Ohio

Application November 4, 1948, Serial No. 149,467

Term of patent 14 years

(Cl. D26—14)

To all whom it may concern:

Be it known that I, Joseph J. Esse, a citizen of the United States, residing at 1617 Lakeland Avenue, Lakewood, in the county of Cuyahoga and State of Ohio, have invented a new, original, and ornamental Design for Phonograph Pickup, of which the following is a specification, reference being had to the accompanying drawings, forming part thereof.

Figure 1 is a perspective view of the phonograph pickup, showing my new design;

Figure 2 is a side elevational view of the phonograph pickup shown in Figure 1;

Figure 3 is a perspective view of the phonograph pickup with a counter-weighting cap removed; and

Figure 4 is a side elevational view of the pickup as shown in Figure 3.

I claim:

The ornamental design for a phonograph pickup, substantially as shown.

JOSEPH J. ESSE.
